UNITED STATES PATENT OFFICE

ALFRED A. GLIDDEN AND THOMAS M. KNOWLAND, OF WATERTOWN, AND ARTHUR M. GREIM, OF DORCHESTER, MASSACHUSETTS, ASSIGNEES TO HOOD RUBBER COMPANY, OF WATERTOWN, MASSACHUSETTS, A CORPORATION OF MASSACHUSETTS

TOP-BOOT AND PROCESS FOR MANUFACTURING

Application filed June 11, 1928. Serial No. 284,302.

This invention relates to an improved top boot and process of manufacture.

The object of the invention is to provide a molded boot with an extended top, the foot and leg of the boot being composed of rubber compound vulcanized in a mold, the top being vulcanized, but not necessarily vulcanized in a mold.

The object of the invention further is to provide a top boot in which the foot and leg portion are manufactured and vulcanized separately from the top portion, and then the two vulcanized members, the boot, including the foot portion and the leg portion, are joined to the top portion in a manner hereinafter set forth. The advantage secured by this construction, and by the method whereby it is secured, is that the top can be made of one type of rubber compound and the leg and foot portion and the sole can be formed of another composition, including the rubber compound and fabric. The top portion may be made only of rubber compound material, or a combination of rubber compound material and fabric, as may be desired.

Another object of the method of this invention is to be able to manufacture a top boot with a substantially thicker all rubber compound top than has heretofore been used, which will stand up without the aid of fastening to the belt, and this type of top also has an advantage, namely, if a man kneels and his knee engages the top portion, it will stretch, whereas the ordinary article, as heretofore manufactured, has a lining which stretches very little, if any, and therefore wrinkles very badly, these wrinkles producing early cracking in the top.

By the method of this invention, the finished boot has a top which is elastic and which may be made in any desired manner with any desired compounds, which it may be desirable to have different from the compounds or compositions of material forming the leg, foot and sole portions of the boot. To these ends, therefore, the boot, including the sole, foot and leg portions, is manufactured and vulcanized separately from the top portion of the boot and then the two vulcanized members, namely, the boot with its leg, and the

top, are subsequently joined together and vulcanized.

In addition to the advantages hereinbefore set forth and attained by our improved process, it will be seen that by separately manufacturing and vulcanizing the boot with its leg, and the top, the most desirable length of time and degree of heat can be utilized for the boot and its leg and for the top, where the boot and its leg are composed of a different compound or different composition of materials from the top as, for example, where the top is composed of a pure rubber compound and the boot may be composed of rubber compound with fabric or other materials embodied therein. The length of time and the degree of heat employed for the boot, in order to properly vulcanize it, especially considering the thickness of the sole of the boot, would be different from the time and degree of heat necessary to properly vulcanize the top, and by our improved process of manufacture we can vulcanize the boot and top separately and obtain the best results for both the boot and the top in this manner, whereas, when the whole boot including the top was vulcanized at one operation, these results could not be attained due to the fact, for example, that the degree of heat and length of time necessary to vulcanize the boot with its thick sole was entirely inadequate for the time and degree of heat required to vulcanize a top which, for example, might be made of pure rubber compound, in which instance the pure rubber compound top when subjected to the degree of heat and for the length of time necessary to vulcanize the boot with its thick sole would be in some cases rendered plastic to an impracticable extent and thus ruined.

The invention consists in the improved top boot and process of manufacture therefor set forth in the following specification and particularly pointed out in the claims.

Referring to the drawings:—

Figure 1 is a blank for the boot top.

Fig. 2 illustrates the blank positioned upon a form.

Fig. 3 is a front elevation broken away and shown in section of the boot top.

Fig. 4 is an enlarged sectional elevation illustrating the lower portion of the boot top and the upper portion of the boot leg spliced together.

Fig. 5 is a side elevation partly broken away and shown in section of the boot without the top portion.

Fig. 6 is a side elevation of an improved form of vulcanizer by which a portion of the process of this invention is carried into practical operation, the same forming the subject matter of a separate application Serial No. 281,884 filed May 21, 1928, entitled "Vulcanizer for top boots", a portion of a boot leg and top positioned thereon and shown in section.

Fig. 7 is an end elevation of the vulcanizer.

Fig. 8 is a wiring diagram for the vulcanizer.

Like numerals refer to like parts in the several views of the drawings.

In carrying our improved process of manufacture into practical operation, a blank 10, Fig. 1, is wrapped around a form 11, as illustrated in Fig. 2, and the edges are cemented 25 together at 12. The boot top 13 is thus formed and is then vulcanized. After it is vulcanized it is trimmed off to the proper height around the bottom edge 14 thereof. The bottom edge is then skived off as at 15, Fig. 3, on the inner 30 face thereof.

The boot 16, comprising a foot portion 17 and a leg portion 18, is vulcanized in a heated mold as shown and described in United States Letters Patent No. 1,692,828, issued November 27, 1928, and subsequently the upper edge is 35 trimmed and skived or buffed off on the outside as at 19. Cement is then applied to the bevelled edges of the boot and the top. The cement is then allowed to dry for about two 40 hours and cement is again applied thereto. The bevelled upper edge of the boot and the bevelled lower edge of the top are then placed together, cement to cement, as evenly as possible and rolled down thoroughly into contact with each other with a hand roller. The open end of the boot thus formed is slipped over a mandrel 20, Fig. 6, and is pulled up 45 snugly on the tapered surface of said mandrel, the spliced portion resting on the mandrel, 50 is then wrapped with a strip of cloth and the boot is then allowed to vulcanize for about twelve minutes; the latter is then removed and the boot is slipped off the mandrel.

Referring to Fig. 6, it will be seen that the sides 21 of the mandrel 20 converge and that the mandrel is oval shaped transversely thereof, as clearly shown in Fig. 7. 22 is a thermometer inserted in the mandrel 20. 23 and 24 are electric heating elements which preferably extend through the mandrel. 25 is an electric control bulb. The mandrel is supported by an elongated bracket 26 which 60 is fastened to a suitable support 27. The

electric heating elements are heated as follows:—Referring to Fig. 8, 20 is the vulcanizer with the converging sides 21, 21. The control bulb 25 is connected through a tube 29 to a Bourdon tube 30 in the thermostat 31. When the temperature of the mandrel arrives at a predetermined degree, the pressure generated by the volatile liquid in the bulb 25 is transmitted through the tube 29 to the Bourdon tube 30, which causes the outer end of the Bourdon tube to move and open a pair of electrical contacts 32 and 33. This opens or closes the heater circuit 34 consisting of a wire 35 which leads in through a fuse box 36 to the contact 32. The other contact 33 is connected by wires 37 to the heaters 23 and 24 and the electric current returns from the heater by wires 38 through a switch 39 and through the fuse box 36, so that as the temperature of the mandrel arrives at a predetermined degree, the heat will be shut off from the heating elements 23 and 24 and when the temperature lowers these heating elements will again be supplied with electric current through the circuit 37.

We claim:

1. A top boot having, in combination, a vulcanized molded foot and leg portion of rubber compound, the upper end of said leg portion being bevelled, and a vulcanized top portion of rubber compound, the lower end of the top portion being bevelled and attached to the bevelled upper end of the leg portion by vulcanizable adhesive material locally vulcanized thereto.

2. The process of manufacturing a top boot which consists in manufacturing a boot of rubber compound and vulcanizing the same, then trimming the upper edge of the boot leg, then beveling the said upper edge, and in manufacturing a boot top of rubber compound and vulcanizing the same, then beveling the lower edge thereof, then attaching the lower edge of the boot top to the upper edge of the boot leg by vulcanizing adhesive material, and then locally vulcanizing the said edges together.

3. A step in the process of manufacturing a top boot which consists in attaching the bevelled lower edge of a boot top of rubber compound to the bevelled upper edge of a boot of rubber compound and locally vulcanizing the said edges together.

4. A step in the process of manufacturing a top boot which consists in locally vulcanizing together the bevelled lower edge of a boot top of rubber compound and the bevelled upper edge of a boot of rubber compound.

In testimony whereof we have hereunto set our hands.

ALFRED A. GLIDDEN.
